UNITED STATES PATENT OFFICE

141,632

DESIGN FOR A TOY SHIP

John T. Cox, Santa Monica, Calif.

Application February 14, 1945, Serial No. 117,939

Term of patent 14 years

(Cl. D34—15)

To all whom it may concern:

Be it known that I, John T. Cox, a citizen of the United States, residing at Santa Monica, in the county of Los Angeles and State of California, have invented a new, original, and ornamental Design for a Toy Ship, of which the following is a specification, reference being had to the accompanying drawing, forming part thereof.

I claim:

The ornamental design for a toy ship, as shown.

JOHN T. COX.
